United States Patent Office.

GEORGE W. MCGILL, OF WASHINGTON, DISTRICT OF COLUMBIA.

Letters Patent No. 63,737, dated April 9, 1867.

IMPROVEMENT IN SPIKES.

The Schedule referred to in these Letters Patent and making part of the same.

TO ALL WHOM IT MAY CONCERN:

Be it known that I, GEORGE W. MCGILL, of Washington, in the county of Washington, and District of Columbia, have invented a new and useful Improvement in Split Spikes; and I do hereby declare the following to be a full, clear, and exact description of the same, reference being had to the accompanying drawings.

My invention consists in making a spike of a single piece of metal, with two opposite shoulders near the point, and split from said shoulders into three prongs up to within a short distance of the head, the centre forming the body of the spike and the side portions the wings. These wings are shorter than the centre or body of the spike, and are bevelled at their ends, each in a contrary direction. When the spike is driven into the wood it goes down perpendicularly, like any ordinary spike, until the points of the wings strike the wood, these wings, as above stated, being joined in the centre or body of the spike only at its top, or head, and bevelled at their points in contrary directions from each other, separate, and follow the course of their bevels horizontally from the centre, or spike proper, which goes down into the wood perpendicularly, thus securing the spike in the strongest possible manner.

I am aware that spikes have been made split up the centre with the points of their shanks so bevelled as to separate when driven into wood similarly to the wings of the spike herein described, but spikes so made depend entirely on the evenness of the grain of the wood into which they are driven for their security and position, for if the grain on one side of the spike is even, and on the other side knotty, the side of the spike entering the knotty grain, on account of the greater resistance it meets with, will necessarily take a more abrupt curve than the other side, thus throwing the spike out of its perpendicular position, which, as will readily be seen, is a fatal objection. In my spike this objection does not exist, for while its wings are spreading the centre or body of the spike enters the wood perpendicularly and holds the entire spike in its proper position independent of the wings, thus combining all the qualities of the old common spike with that of the split.

I will now proceed to describe the accompanying drawings.

Figure 1 represents a perspective view of the spike. A is the head, B the centre or body, C C the wings, D D the bevelled points. These points can be bevelled on a curve or angle, and of any degree, or with points shaped like the top quarter of a cone or quarter of a four-sided pyramid, as represented by the dotted line d', but I prefer a curved angle, such as herein represented.

Figure 2 is a perspective view of the spike, representing the course or curve taken by its wings when it is driven into the wood.

Figure 3 is a front view of the same.

Figure 4 represents the spike with its prongs or wings bevelled from the top of the split to their points, near which the bevel becomes more abrupt.

Figure 5 represents the spike with the splits wide. The points of the prongs may also be so bevelled as to make them separate in the same plane from the body of the spike, as represented by the dotted lines E and E', in this figure.

I am aware that spikes have heretofore been made with their points split into three parts or prongs, and the side prongs so bevelled as to spread or diverge on being driven into the wood; but in all cases of this kind of which I am aware the centre prong has been made no longer than the side prongs, and the splits have only been extended a short distance from the point. It is manifest that when the entire prong is no longer than the side prongs it will not so effectually tend to guide the spike and keep it in a perpendicular position on being driven into the wood, as in the case of my spike, with its centre prong extending a considerable distance below the bevelled side wings. It is also manifest that when the split extends only a portion of the way up towards the head from the point, leaving the upper portion of the shank or body of the spike undivided, the spike cannot be driven into the wood without first boring a hole in which to insert it. But in my spike I extend the splits up towards the head as far as the spike is to be driven into the wood, which enables me to drive it into the wood without boring.

I therefore disclaim such forms of spikes as I have above described and admitted to be old, but what I do claim, and desire to secure by Letters Patent, is—

1. A spike split into three parts or prongs, the centre prong being longer than the side prongs, and said

side prongs being so bevelled that on being driven into the wood they will spread and diverge from the centre prong in opposite directions, while the said centre prong goes down into the wood perpendicularly, substantially as shown and described.

2. A spike split into three parts or prongs throughout the whole extent of the shank that is to be driven into the wood, with the side prongs bevelled, as described, so that the spike may be driven into the wood, and the side prongs made to spread and diverge without boring, substantially as described.

GEORGE W. MCGILL.
